UNITED STATES PATENT OFFICE.

CARLTON C. SIGLER, OF CLEVELAND, OHIO.

PAPER CLIP.

Application filed October 13, 1926. Serial No. 141,294.

This invention relates to improvements in paper clips, and more particularly to clips which are formed by bending a continuous wire into open loops, two of which loops extend in the same direction and have their ends spaced a comparatively short distance apart, said loops being capable of being spread apart laterally of the clip thereby to receive several sheets of paper therebetween.

It is the general purpose and object of the invention to provide a clip of this character which will enable several sheets of paper to be fastened firmly together and one which, when so applied to said sheets, will prevent other sheets from slipping between the gripping ends of the loops and the sheets clamped thereby. Further and more limited objects of the invention will be set forth hereinafter and will be realized in and through the construction and arrangement of parts shown in the drawings, wherein Fig. 1 represents a plan view of a portion of one or more sheets of paper having one of my clips applied thereto; Fig. 2 a plan view and Fig. 3 a side elevation of the said clip; Fig. 4 a side elevation of the clip and paper shown in Fig. 1.

Referring to the form of my invention shown in Figs. 1 to 4 inclusive, the clip as a whole comprises a resilient wire having the portions 1, 2, 3, 4, 5, 6, 7, 8, 9 and 10. The portions 1, 2 and 3 are so bent as to provide a pair of converging legs 1 and 3 and a connecting member 2 for the divergent ends of said legs, the said parts forming an open loop having the part 2 deflected upwardly and above the plane of the parts 1 and 3 forming a hump. The legs 3 and 5 are connected at their convergent ends by a narrow bend 4 forming a second open loop extending in the opposite direction from the first loop. The wire of which the clip is formed is further bent at 5, 6 and 7 to form a third open loop which is wider than the first loop and which encloses the widened part of such first loop. The part 6 of this third loop is bent downwardly and out of the plane of the parts 1, 3, 5 and 7, to form a hump projecting in the opposite direction from the hump 2, the said humps projecting transversely of the plane of the clip. The part 7 is bent upon itself at 8, forming a bar or leg 9 which is preferably parallel with the leg 7 and the end of which is bent at substantially right angles to provide a sharp point or pin

10 of sufficient length to extend through several sheets of paper. The parts 8 and 9 constitute a loop which is located outside of the loops 2, 4 and 6.

The clip is applied to two or more sheets of paper by springing the parts 2 and 6 apart, so that the downwardly projecting hump 6 will engage the top of the uppermost sheet while the upwardly projecting loop or hump 2 will engage the underside of the bottom sheet, thus clamping the sheets between the humps 2 and 6 on the jaws provided by the closed ends of the loops. By bending the sheets 11 and 12 downwardly on that side of a clip which carries the arm 9 and pin 10, as the clip is being slipped over the sheets, the point or pin 10 can be slipped along the top sheet without difficulty, after which it can be pressed through the sheets by straightening up the latter and pressing down upon the arm or leg 9.

With this construction of clip, the sheets will be clamped securely between the oppositely extending humps on the jaws formed by the closed ends 2 and 6 of the corresponding loops, thus enabling the clip to clamp the sheets firmly and also to prevent the accidental insertion of sheets between said humps or loop ends and the sheets which are secured together thereby. Furthermore, as the point or projection 10 extends at right angles to the body of the clip, it will secure the sheets together in the manner of a pin and thus prevent their unintentional removal from the clip.

When it is desired to remove the clip, the paper on the side thereof which carries the pin or point 10 may be bent downwardly to disengage it from such point and the parts 2 and 6 may be then separated a sufficient distance to enable the sheets to be removed.

Reference has been made hereinbefore to the divergence of the wires 1 and 3, 5 and 7 toward the ends or humps 2 and 6 of their respective loops and to the convergence of the legs 3 and 5 toward the end 4 of the oppositely extending loop. This enables me to secure a firmer gripping engagement between the legs 1, 3, 5 and 7 and the paper interposed between the gripping loops than if a clip of the ordinary shape were employed. Unless the sheets to which the clip is applied are particularly stiff, the humps 2 and 6 will bend the paper in opposite directions, enabling the legs of the clamping loops to engage opposite sides of the sheets.

In Fig. 4, for clearness of illustration the legs forming the sides of the clamping loops are shown as spaced from the sheets 11 and 12. In practice, however, unless the sheets be particularly stiff, these legs will engage the sheets and will provide a firmer gripping engagement with said sheets, even without the humps 2 and 6, than can be secured by the ordinary clip.

- 10 Having thus described my invention, what I claim is:—
1. A paper clip consisting of a continuous wire bent to form an outer loop and an inner loop continuous therewith, the said loops extending in the same direction and being connected by a loop extending in the opposite direction, the wire forming one side of the outer loop being bent upon itself to form a loop outside of said loops and the 20 extreme end of such wire being bent at substantially a right angle to the plane of the clip and providing a projection of sufficient

length to be inserted through several sheets of paper.

2. A paper clip consisting of a continuous wire bent to form an outer loop and an inner loop continuous therewith, the said loops extending in the same direction and being connected by a loop extending in the opposite direction, the wire forming one side of the outer loop being bent upon itself to form a loop beside said loops and the extreme end of such wire being bent at substantially right angles to the plane of the clip and providing a projection of sufficient length 35 to be inserted through several sheets of paper and the ends of the outer and inner loops being deflected in opposite directions transversely of the plane of the clip to provide humps adapted to grip the said sheets 40 firmly therebetween.

In testimony whereof, I hereunto affix my signature.

CARLTON C. SIGLER.
